PROCESS OF AND MEANS FOR MAKING MATCHES

Filed Aug. 2, 1929

UNITED STATES PATENT OFFICE

JOHN R. NOLAN, OF NEW YORK, N. Y., ASSIGNOR TO THE DIAMOND MATCH COMPANY,
OF CHICAGO, ILLINOIS, A CORPORATION OF ILLINOIS

PROCESS OF AND MEANS FOR MAKING MATCHES

Application filed August 2, 1929. Serial No. 383,077.

The present application is a continuation in part of my application Serial No. 272,891, filed April 26, 1928.

This invention relates to a process of and means for making matches having splints of permeable combustible material; its object being to provide for the economical and efficient treatment of the splints with a material, such as sodium silicate or ammonium phosphate, which is effective to limit the flame to a relatively small portion of the splint when a match is ignited, thus minimizing the fire hazard should the match be negligently discarded before the extinguishment of the flame.

The invention is especially designed for use in connection with a match making machine of the class wherein the splints are inserted endwise, row by row, in an endless carrier and thereby rigidly held in spaced parallel relation and transported through the match making path, including wax (as paraffin) and head-composition applying mechanisms.

In carrying out the invention in the preferred way the lower ends of the depending match splints, supported in spaced parallel relation, are dipped into molten wax, as paraffin, to a depth substantially corresponding with the desired inflammable area of the splints. The splints are then exposed to the atmosphere for a brief interval to allow the wax to set. They are then dipped into or sprayed with a free flowing fire-resisting liquid, such as sodium silicate or ammonium phosphate, to a depth substantially co-extensive with or greater than the length of the waxed surfaces. The splints are then inverted, thus causing the liquid to flow from such waxed surfaces to and upon the adjacent unwaxed portions of the splints, which portions thereupon absorb the liquid and are rendered noncombustible thereby. The free extremities of the splints are next tipped with ignitable composition or compositions to form

the match heads. The matches thus produced are conveyed through a suitable drying space, whence they are discharged from the carrier and packed.

Figures 1 and 2 of the drawings are illustrative diagrams of parts of a match making machine designed to carry out my hereinbefore described process. In the drawings, 1 designates a portion of an endless carrier in which match splints, 2, are endwise inserted, 50 row by row, and thereby rigidly held in spaced parallel relation. 3 designates a bath of molten paraffin, or the like, in which the lower ends of the depending splints are immersed to a predetermined depth during the 55 progress of the carrier.

4 (Fig. 1) designates a bath of free flowing fire-resisting liquid, in which the splints are immersed a suitable depth. The baths are sufficiently spaced to permit the paraffin to 60 set before the liquid of the second bath is applied. 5, 6 designate two suitably-disposed wheels about which the carrier is flexed so as to travel in a reverse direction in a horizontal path immediately after it leaves the fire- 65 resisting liquid, thus inverting the paraffined ends of the splints and causing the liquid to drain from the paraffined surfaces to the adjacent lower portions of the splints. 7, 8 designate respectively a suitably-disposed seg- 70 mental guide and wheel about which the carrier is next trained so as to travel downwardly and horizontally. 9 designates a composition-containing tank equipped with a transfer roll 10 by means of which head 75 composition is applied to the lower paraffined ends of the depending splints during the horizontal travel of the carrier from the wheel 8.

It may be added that the vibration of the travelling carrier tends to contribute to the 80 removal of the liquid from the paraffined surfaces of the inverted splints, which vibratory effect may be augmented, if desired, by the provision of a jarring device co-acting with the rum of the carrier between the wheels, 5, 6. 85 90

In the construction shown in Fig. 2, is employed a spayer 40, instead of the bath 4, for applying fire-resisting liquid to the splints after they leave the paraffin bath, which sprayer is protected by means of a casing 11 having a drip pan 12. The sprayer is preferably arranged to project the liquid longitudinally of the horizontally-disposed splints as they pass about the guide wheel 5.

10 I claim—

1. A process of making matches, comprising applying wax to a portion of a splint at one end of the latter, applying a free flowing fire-resisting liquid to such end to a greater extent than the wax, causing the liquid to flow from such portion to and upon the unwaxed part of the splint, and applying head composition to the free end of such waxed portion.

2. A process of making matches, comprising applying wax to a portion of a splint at one end of the latter, applying a free flowing fire-resisting liquid to such portion, causing the liquid to flow from such portion to and upon the unwaxed part of the splint, and applying head composition to the free end of the waxed portion.

3. A process of making matches, comprising applying wax to a portion of a splint at one end of the latter, applying a free flowing fire-resisting liquid to such portion, inverting the splint to cause the liquid to flow from such portion to and upon the adjacent portion of the splint, and applying head composition to the free end of the waxed portion.

4. A process of making matches, comprising applying wax to a portion of a splint at one end of the latter, applying a free flowing fire-resisting liquid to such portion, inverting the splint to cause the liquid to flow from such portion to and upon the adjacent portion of the splint, returning the splint to its previous position with the waxed portion extending downward, and applying head composition to the free end of the waxed portion.

5. In a match machine, the combination with a carrier for match splints, of a bath adapted to contain wax in which the depending ends of the splints borne by the carrier are dipped to a limited depth, means for applying a free flowing fire-resisting liquid to the waxed portions of the splints, means for positioning the carrier to cause the liquid to flow from the waxed surfaces to and upon the unwaxed parts of the splints, and means for applying head composition to the waxed ends of the splints.

6. In a match machine, the combination with a carrier for match splints, of a bath adapted to contain wax in which the depending ends of the splints borne by the carrier are dipped to a limited depth, means for applying a free flowing fire-resisting liquid to the waxed portions of the splints, means for deflecting the carrier to invert the splints to

cause the liquid to flow from the waxed surfaces to and upon the adjacent portions of the splints and then deflecting the carrier to position the splints with their waxed ends extending downward, and means for applying head composition to the waxed ends of the splints.

Signed at New York, in the county and State of New York, this first day of August, A. D. 1929.

JOHN R. NOLAN.
